UNITED STATES PATENT OFFICE.

NORMAN COOK, OF MANCHESTER, ENGLAND.

LAPPET AND THREAD GUIDE OF SPINNING, TWISTING, AND LIKE MACHINES.

Application filed September 27, 1924, Serial No. 740,326, and in Great Britain September 28, 1921.

This invention relates to lappets and thread guides for spinning, twisting, and like machines, and its object is to provide an improved and economical form of metal 5 lappet of the kind in which the thread guide is secured by a screw abutting against the shank of the said guide.

According to this invention the lappet is formed of sheet metal the forward portion 10 of which is bent down, back, and upward until its edge is in close contact with or is situated immediately beneath the under face of the metal forming the lappet, the bent metal thus forming a tube or open-ended 15 cylinder of small diameter extending across the forward portion of the lappet and below the upper surface thereof; the said tube is provided with holes bored transversely thereof to receive the shank of the thread 20 guide and the inner walls of the said tube are tapped, on one or both sides of the transverse holes, to accommodate a grub screw or other set screw adapted to bear against the portion of the shank that crosses the 25 tube, thus clamping the thread guide in position.

In the accompanying drawings—

Figure 1 is a side elevation,

Figure 2 is a front elevation, with the 30 shank of the thread guide shown in section, and

Figure 3 is an inverted plan of one construction of lappet and thread guide according to this invention.

Figures 4 and 5 are views of details.

A is a lappet, which is secured at its rear end to a lappet board B by a screw passing through a hinge member C, and which carries at its forward end a thread guide D formed of wire bent as shown. The lappet A is made of sheet metal and comprises a top plate a and side flanges a^1 a^1 which form bracket supports for the lappet when in its horizontal position as shown in Figure 1.

a^3 is a tube extending across the front of the lappet and formed by bending the for-

ward portion of the top plate into the position shown. The said tube a^3 has two holes bored transversely through it, and on the centre line of the lappet, to receive the shank D¹ of the thread guide D; and one or both ends of the tube a^3 are tapped to receive a grub screw E (Figure 4) the forward end of which is screwed tightly against the portion of the shank D¹ that lies within the tube a^3 and thus clamps the thread guide in the required position.

Having described my invention what I claim and desire to secure by Letters Patent is:—

1. In a lappet and thread guide for spinning, twisting and like machines the combination with a thread guide of a lappet having a metal plate the forward portion of which is bent to form a cylindrical bushing the interior of which is tapped and in the walls of which are cut oppositely situated holes on a line transversely of the bushing, the said holes being adapted to receive the shank of the thread guide, and a set screw adapted when screwed into the bushing to abut against the portion of the thread guide shank that crosses the said bushing.

2. In a lappet and thread guide for spinning, twisting and like machines, the combination with a thread guide of a lappet comprising a metal plate provided at its forward end with an axially interiorly threaded bushing, said bushing being transversely apertured to admit the shank of a thread guide, a thread guide in the apertured part of said bushing intersecting the bore of said bushing and a set screw screwing directly axially into said bushing, and coacting directly with that portion of the shank of the thread guide which lies in its path.

Signed at Manchester, in the county of Lancaster, England, this first day of August, A. D. 1922.

NORMAN COOK.
